UNITED STATES PATENT OFFICE.

JOEL CADBURY AND JOSEPH GEORGE ROLLASON, OF BIRMINGHAM,
ENGLAND.

ALARM-LOCK.

SPECIFICATION forming part of Letters Patent No. 394,831, dated December 18, 1888.

Application filed August 13, 1887. Serial No. 246,825. (Model.) Patented in England May 27, 1886, No. 7,099.

To all whom it may concern:

Be it known that we, JOEL CADBURY and JOSEPH GEORGE ROLLASON, manufacturers, subjects of the Queen of Great Britain, residing at Birmingham, England, have invented certain new and useful Improvements in Alarm Locks and Latches, (for which we have obtained Letters Patent of Great Britain, dated May 27, 1886, and numbered 7,099,) and we do hereby declare the following to be a full, clear, and exact description of the invention, reference being had to the accompanying drawings, which form part of this specification.

This invention has for its object the ringing of a bell, or the creating of an alarm, on a person entering or leaving a room by the door. The act of turning a knob or handle for the withdrawal of the latch-bolt of a lock or latch gives an alarm and indicates the exit or entrance of a person.

Figure 1 represents in front elevation an alarm or ringing lock constructed according to our invention. Fig. 2 shows a like view as Fig. 1, but with the alarm or ringing mechanism thrown out of action by the lowering of one end of the latch-bolt which works the ringing mechanism. Fig. 3 shows a vertical section of the said lock, and Fig. 4 shows the pallet of the verge and a portion of the face-

30 wheel upon a larger scale, while Fig. 5 represents our improvement applied to a latch.

Thus in Fig. 1 the act of turning the handle or knob of a door, or the act of pressing back the latch-bolt, raises an alarm by the ringing 35 of the bell; and should a person clandestinely or otherwise open a door by the knob or by the pushing back of the latch, the act is at once detected. The throwing-out-of-gear arrangement is to prevent ringing when no 40 alarm is wanted—that is, at ordinary times.

The same letters of reference indicate corresponding parts in the several figures of the drawings.

a is an ordinary lock-casing provided with 45 the usual lock-bolt, *b* and latch-bolt *c*, which move in a horizontal plane. The latch-bolt *c* is suspended at its back end by a pivoted hanging arm, *d*, upon which a latch-follower, *e*, acts and presses on the same, being partially 50 rotated on the turning of a knob secured upon a spindle, *e*², passing through the bushed eye of the said follower.

f is an ordinary flat spring for the bringing back of the parts to their normal positions.

g is a face-wheel with a double row of reversed V-shaped teeth, which gives a rapid intermittent motion to the pallet *h*² of a verge, *h*, on the said face-wheel being rotated, and it is through the verge *h* that the hammer *i* is operated and made to strike rapidly the lip 60 of a bell, *j*.

Rotary motion is imparted to the face-wheel, as aforesaid, by a pinion, *k*, on its axis *g*², gearing with the teeth of a rack, *c*², on the upper edge of the latch-bolt *c*, so that on 65 the latch-bolt being worked a very rapid reciprocation is given to the hammer by the double row of teeth of the said face-wheel acting alternately upon the pallet of the verge, thus pushing the said pallet aside or from 70 tooth to tooth, and so giving the necessary oscillatory motion.

The face-wheel *g* remains stationary when its axis and ratchet-wheel are rotated in a backward direction, but turns with the axis 75 and ratchet-wheel when rotated in a forward direction (as indicated by the arrow) by the pawl *l* engaging with the teeth of the said ratchet-wheel, like that of an ordinary chronometric instrument. The pawl is kept up 80 to its work by a spring, *p*.

The ringing mechanism is thrown out of gear—when no alarm or surprise is required—by a slide, *o*, with a knob, *o*², passing through a slot, *a*², in the lower under side of the lock-case. The fore part of the slide has a turned end, *o*³, which, when out of position, comes beyond a rise or swell, *c*³, on the under side of the latch-bolt *c*; and to admit of the end lowering of the said bolt, as represented in 90 Fig. 2, a long hole, *c*⁴, is made, wherein a stud, *d*², on the lower end of the hanging lever *d*, takes.

Having thus described our invention, we claim as new and desire to secure by Letters 95 Patent—

1. In an alarm-lock, the combination, with a movable latch or bolt having teeth, a ratchet-wheel and pinion engaging with said teeth, of an escapement and striker engaging with said 100 wheel and a bell arranged in proximity to said striker, all substantially as described.

2. The combination, with a lock or latch case, *a*, latch-bolt *c*, and knob spindle or fol-

lower e e^2 , of bell-ringing mechanism consisting of face-wheel g , with double row of reversed V-shaped teeth, verge h , pallet h^2 , hammer i , bell j , pinion k and its axis g^2 , 5 ratchet-wheel m , rack-teeth c^2 on latch-bolt, and pawl and spring l^2 , substantially as described and set forth.

3. In an alarm-lock, the combination, with a toothed latch or bolt and a bell, of a striker, 10 an escapement operating the same, an escapement-wheel, a pinion on the shaft of said wheel, and a dog or pawl-and-ratchet connection between said pinion and escapement-wheel, whereby the latter will be turned only by the 15 movement in one direction of said latch, substantially as described.

4. In an alarm-lock, the combination, with the longitudinally-movable toothed bolt c , having slot c^1 and rise c^2 , of the pinion g^2 , the alarm mechanism connected therewith, and 20 the sliding plate o , adapted to engage with rise c^2 , substantially as described, so as to bring said pinion into engagement with the bolt c , as set forth.

Signed this 20th day of June, 1887.

JOEL CADBURY.

JOSEPH GEORGE ROLLASON.
